Inventor

James J. Kelly
Attorney

UNITED STATES PATENT OFFICE

2,483,979

ELECTRIC NURSING BOTTLE WARMER

Lewis H. Morrill, Los Angeles, Calif.

Application April 7, 1947, Serial No. 739,823

1 Claim. (Cl. 219—44)

1

The present invention relates to electric nursing bottle warmers, and its primary object is to provide a device adapted for use with any standard wide-mouthed nursing bottle, which enables the bottle to be sterilized, filled, and stored in a refrigerator until needed, and then warmed up quickly to the desired temperature by merely connecting an electric cord to the device for a few minutes before offering the bottle to the infant. The principal advantage of the invention is in the speed and convenience with which the bottle of milk may be warmed up to the desired temperature, which is particularly advantageous in the case of nocturnal or early morning feedings, and also in the fact that the nipple and contents of the bottle are kept absolutely sterile up to the time the bottle is ready for use. Another important advantage of the invention is that it provides an exceedingly convenient means for warming the bottle when traveling or away from home, since the unit is entirely self-contained and the only requisite is an electric outlet.

In its preferred form, the present invention comprises an elongated, immersion-type heating element mounted on a flanged base member which is clamped against the mouth of the bottle by means of a retainer ring that is screwed onto the bottle neck. In one of its forms, the flanged type of nipple used with wide-mouthed bottles is clamped between the retainer ring and the base member of the heating element, while in another form, the retainer is provided with a projecting annular flange or neck to receive the more common type of nipple used with conventional small-mouthed nursing bottles. In both of these embodiments, suitable passages are provided in the base member to permit milk to flow from the bottle to the nipple. The resistance wires of the heating element are carried through the base member and retainer ring, and terminate in contact points which are engaged by other contact points in a removable, nipple-covering cap member having a bayonet connection with the retainer ring. The contact points of the cap member are connected to a pair of laterally spaced, parallel prongs which project from the cap and are adapted to receive a connecting socket plug on the end of an electric cord.

When the sterilized bottle is filled with milk, the heating element and nipple are assembled on the bottle, and the cap member is inserted over the nipple and secured to the retainer ring. The bottle can then be stored in the refrigerator until needed, with absolute assurance that the nipple and contents of the bottle will remain sterile.

2

When needed, the bottle is merely removed from the refrigerator and an electric cord socket plugged onto the prongs of the cap member until the resistance heating element has warmed the milk up to body temperature. The cord is then disconnected, the cap member is removed, and the bottle offered to the infant.

Another object of the invention is to provide a bottle warming attachment which is inexpensive, 10 easily cleaned, and convenient to use, and which can be used interchangeably with any standard wide-mouthed nursing bottle so that the same unit may be used successively with any number of bottles, making it unnecessary to purchase 15 more than one unit per family.

Other objects and advantages of the invention will become apparent to those skilled in the art upon consideration of the following detailed description of two selected embodiments thereof, 20 reference being had to the drawings, in which:

Figure 1 is a sectional view taken through a nursing bottle having an electric heater embodying the principles of the invention mounted thereon;

Figure 2 is a fragmentary sectional view of the same, showing the protective cap removed;

Figure 3 is a top plan view of the bottle warmer; and

Figure 4 is a sectional view of another embodiment of the invention.

In Figures 1 to 3 of the drawings, the reference numeral 10 indicates a nursing bottle of the wide-mouthed type having a neck portion 11, with threads 12 formed on the outside thereof. The 35 electric bottle warmer of the invention is designated in its entirety by the reference numeral 13, and comprises a base member 14, having a radial flange 15 which extends over the end of the bottle mouth. Projecting downwardly from the underside of the base member 14 is a cylindrical boss 16, and mounted on this boss is a heating element 17 which is contained within a thin-walled metal tube 20. The tube 20 is pressed onto the boss 16 and projects downwardly therefrom into the interior of the bottle.

Resistance wires 21 and 22 are disposed within the interior of the tube 20, and their upper ends are embedded in the boss 16 of the base member 14. In the preferred form of my invention, there 50 is a thermostat of any conventional form which is contained within a bulb extension 23 formed at the bottom end of the tube 20, said thermostat being connected serially with the resistance wires 21, 22 in the usual manner by lead-in wires 24. Such a thermostat is not essential to the inven-

tion, however, and may be dispensed with if so desired.

A nursing nipple 25 of the type used with wide-mouthed bottles is mounted on top of the base member 14, and has a radial flange 26 which lies on top of the base member flange 15. A second flange 30 projects radially from the base of the nipple a short distance above flange 26 and cooperates with the latter to form a channel 31.

The nipple 25 and base member 14 are clamped to the bottle mouth by means of an annular retainer ring 32 having internal threads 33 which are adapted to be screwed onto the bottle threads 12. At the top end of the retainer ring 32 is a radially inwardly projecting flange 34 which overlies the nipple flange 26 and extends into the channel 31. An annular groove 35 is formed on the inside of the retainer ring above the top end of the threads 33, and seated within this groove is a resilient gasket 36 of rubber or like material which is disposed between the base member flange and the end of the bottle and serves to seal the joint against leakage. The gasket 36 also serves as a retaining ring to hold the base member 14, nipple 25, and retainer ring 32 together when the assembly is removed from the bottle, and is assembled in the groove by buckling or collapsing the ring to force it down past the threads 33 and into the groove 35. One or more fluid passages 40 are provided in the flange 15 of the base member to permit the fluid in the bottle to flow through to the nipple 25.

The upper ends of the resistance wires 21, 22 are connected by wires 41 and 42, respectively, to two spaced contacts 43 and 44 which project upwardly from the top surface of the base member flange 15 through holes 45 and 46 in the nipple flange 26 and retainer ring flange 34, respectively. A cap member 50 is provided which is adapted to be secured on the retainer ring 32 so as to cover the nipple 25 and protect the latter against contamination while the bottle is stored in a refrigerator or being transported. The cap 50 is provided with an annular skirt 51 having two bayonet slots 52 formed in its inner surface at opposite sides thereof, said slots being engageable with lugs 53 projecting from opposite sides of the retainer ring 32. The cap member 50 is provided with a downwardly facing shoulder 54 which engages the top surface of the retainer ring flange 34 when the cap is secured on the ring by its bayonet connection. A domed portion 55 on the top of the cap covers the nipple 25, and is provided at the top with a vent hole 56 to permit the escape of any steam or vapor pressure that may build up as a result of heating the fluid contents of the bottle.

The shoulder 54 is recessed at 60 to provide clearance for the projecting ends of the contacts 43, 44 which extend slightly above the surface of the retainer ring flange 34, and embedded in the body of the cap with their ends projecting downwardly into the recess 60 so as to register with the contacts 43, 44 are contact points 63 and 64. The contact points 63, 64 are connected to two laterally spaced, parallel connector prongs 65 and 66 which project from one side of the cap member 50. The prongs 65, 66 are adapted to receive a two-hole connector socket 70 on the end of an electric extension cord 71 which, when connected to an electric outlet, supplies current to the heating element. The bayonet lugs 53 and slots 52 are located so that when the cap member 50 is secured on the retainer ring, the contact points 63, 64 engage the contacts 43, 44.

The heating unit and nipple of the invention are assembled on the nursing bottle 10 at the time the latter is sterilized and filled, and the cap member 50 is secured on the retainer ring to protect the nipple from contamination while the nursing bottle is stored in the refrigerator or being transported. When the bottle is needed, the connector plug 70 of an electric cord 71 is plugged onto the prongs 65, 66. Current from the line is transmitted to the resistance wires 21, 22 of the heating element 17, warming the contents of the bottle until the current is cut off by the thermostat in bulb 23, which should preferably be set to maintain a temperature of approximately 98° to 100° F.

When the bottle has been warmed to the desired temperature, the connector plug 70 is removed from the prongs 65, 66, and the cap member 50 is removed from the retainer ring. The bottle is then ready to be offered to the infant.

Another form of the invention is shown in Figure 4 which illustrates an arrangement utilizing the conventional nipple used with the more common small-mouthed nursing bottle. In this embodiment, the base member 14 is identical to the one in the preceding embodiment, and is secured on the mouth of the bottle 10 by means of an annular retaining member 75 having a flat top portion 76 which overlies the flange 15 of the base member 14. Disposed between the top wall 76 and flange 15 is a rubber sealing gasket 80 having holes 81 through which the contacts 43, 44 project. The top portion 76 of the retainer is also provided with holes 82 which align with the holes 81, and the contacts 43, 44 extend to a point elevated slightly above the top surface of the wall 76. Extending upwardly from the center of the top wall portion 76 of the retainer is an annular neck 83 having a radial flange or bead 84 around its top edge. The nipple 85 is provided on its inner surface with two vertically spaced, inwardly projecting flanges 86 and 87 which cooperate to form a channel 90 seating on the flange 84.

As in the preceding embodiment, the retainer has a downwardly extending skirt 91 which is threaded on its inside surface to engage the threads 12 of the bottle neck, and projecting outwardly from opposite sides of the skirt portion are bayonet lugs 53 which are adapted to engage the bayonet slots of cap member 50. Except for the manner of securing the nipple 85 to the retaining member 75, the construction and operation of the embodiment shown in Figure 4 is otherwise the same as in the preceding embodiment.

While I have shown and described in detail two selected forms of my invention, it is to be understood that these embodiments are merely illustrative and that various changes may be made in the shape and arrangement of the several parts without departing from the scope of the broader claim appended hereto.

I claim:

An electric heater for use with a wide-mouthed nursing bottle having a screw-threaded neck, said heater comprising a radially flanged base member adapted to be mounted on the mouth of the bottle, a resistance heating element projecting downwardly from the underside of said base member into the interior of the bottle, a nipple having a radial flange adapted to lie against the flange of said base member, a retainer ring adapted to be screwed onto the threads of the bottle neck and having a flange extending radially inward so as to overlie said nipple flange and

thereby clamp the nipple and said base member to the bottle, a pair of spaced electrical contacts connected to said heating element and projecting upwardly from the top of said base member through holes in the flanges of said nipple and said retainer ring, a cap member adapted to be secured on said retainer ring and covering said nipple to protect the same against contamination, a pair of contacts on the inside of said cap member engageable with said first-named contacts, and a pair of prongs connected to said last-named contacts and adapted to receive a socket connector on an electric cord.
